UNITED STATES PATENT OFFICE

FRANK OBERST, OF FOSTERDALE, NEW YORK, ASSIGNOR TO WILBUR PRODUCTS COMPANY, A CORPORATION OF NEW YORK

AUTOMATIC STOP DEVICE

Application filed June 14, 1929. Serial No. 370,798.

This invention relates to stop devices for phonographs.

It is among the objects of the present invention to provide an improved universal automatic non-set stop which is simple in construction and operation and which will be efficient and durable and well designed to meet the demands of economic manufacture, and which is adapted for use with any type of sound record.

Numerous other objects of the present invention include the novel combination and inter-relation of parts whereby an automatic stop is provided which effectively acts to stop the turntable rotation at the cessation of the playing period regardless of variations of the diameter of the fast portion of the sound groove and regardless of the characteristics of the spiral or eccentric rapid termination groove.

A further important object of the present invention is to provide a stop device which includes means for retaining the members in operative relation whereby handling of the phonograph will not permit the parts to move by gravity to inoperative position. The means of the present invention for accomplishing this object includes a spring urged latch member movable only by associated parts to release the device for stopping movement.

These and other objects of the present invention will be apparent from a consideration of the following specification and accompanying drawings in which:

Fig. 1 is a top plan view of one form of my present invention applied to a portable type phonograph and with a portion of the turntable broken away;

Fig. 2 is a view of the turntable and stop mechanism just prior to the stopping action;

Fig. 3 is a similar view of the stop in operative position; and

Fig. 4 is a perspective view of the stop mechanism.

Referring more particularly to Fig. 1 of the drawings, the embodiment of the invention herein disclosed is for convenience illustrated in conjunction with a portable

type phonograph, the tone arm 10 and turntable 11 of which are the only features which coact with the stop in the operation of the invention. It is therefore not deemed requisite that a detail description of conventional associate structure be made. It will be understood that the invention is applicable to many various forms of phonographs and that the invention is not limited to the type here illustrated.

The stop mechanism includes two independently mounted associated cooperating parts,—an arm 12 mounted at the base of the tone arm 10 for movement therewith and a depending projection 13 extending from the lower face of the turntable 11 approximately halfway between the center and peripheral edge thereof. The function and operation of the arm 12 and projection 13 will be hereinafter described. It will be understood that their configuration as well as the configuration and design of associated parts may undergo various changes without departing from the spirit or scope of the appended claims.

Referring to the main portion of the stop mechanism illustrated in perspective in Fig. 4, the same includes a base 14 securable to the motor board of a phonograph by threaded securing members 15 as shown in Fig. 1. The body 14 is preferably of flat sheet metal and is of tapering shape to provide a tapering end 16 upon which is mounted a headed guide pin 17. The opposite end of the body is wider and includes upwardly bent stop detents 18 and 19 oppositely disposed and rising from the sides of the body. The end of the body is provided with a spring securing projecting support 20 adjacent to which a brake pivot 21 is provided. Intermediate the ends of the body a pivot 22 is provided for the actuating arm 23.

The actuating arm 23 is centrally pivoted upon the pivot 22 and includes an inwardly extending arm 24 terminating in a triangular projection engaging head 25 and a brake-engaging arm 26 terminating in an angularly disposed brake contacting surface 27. Adjacent the pivoted portion of the arm 23 there is provided a controller carrying arm 160

28 terminating in a headed controller pin 29, which extends through an elongated aperture in the inner end of the controller 30.

5 The controller 30 is mounted jointly on the body 14 and the arm 28 for respective movement to each by the provisions of the headed members 17 and 29 extending through the respective elongated apertures 10 31 and 32 thereof. Adjacent the aperture 31 a pair of extending fingers 33 are provided which co-operate with the arm 12 for controlling the mechanism as will be herein described.

15 For preventing accidental outward movement of the controller 30 to inoperative position whereby the arm 12 would abut the inner face of the inner finger 33, the controller is provided with a pivoted latch 41, 20 the outer end of which is turned to provide the vertical surface 42, while the inner end of the latch 41 extends downwardly to provide the latching detent 43. The assembly further includes a latch spring 44 which 25 normally urges the detent 43 towards a receiving notch 45 cut in the side of the member 14.

It will readily be seen that the latch assembly is such that when the controller is 30 in the normal at rest position shown in Fig. 1 that the detent 43 is received in the notch 45 thus holding the controller in operative position. When the arm 12 moves to the 35 position shown in Figs. 2 and 3 it will be seen that the extremity of the arm will strike the vertical surface 42 of the latch 41 and will move the latch about its pivot and against the tension of its spring 44 thus releasing the detent 43 from the notch 45 and 40 permitting movement of the controller with respect to the body 14.

The mechanism is completed by the provision of a pivoted frictional brake 35 which is pivoted to the body 14 by the pivot 21 and 45 which includes a disc engaging flange 36 upon which is secured suitable friction material 37 and an oppositely disposed handle 38 together with an actuator flange 39 to which a spring 40 is secured and extends to 50 the securing flange 20.

In the operation of the device the normal at rest position of the tone arm, turntable and stop mechanism is shown in Fig. 1. In this position the arm 12 is out of engagement with the fingers 33 of the controller 30. The controller is in inward position with respect to the body 14 and the arm 23. The arm 23 is in clockwise rotated position, the stop 18 being against the arm 26 and the 55 brake is in braking position with the flange 36 pressing the material 37 against the inner face of the turntable flange. The position of the brake is maintained by the spring 40 which exerts its tension between the body 14 and brake 35 in a line outside of the pivot 21.

When it is desired to play the instrument, the tone arm is arranged in the usual manner and the brake 35 is rocked about its pivot 21 to disengage the same. This disengaged position of the brake 35 is maintained during the playing period by the change of line of tension by the spring 40 inside the pivot 21 as shown in Fig. 2.

During the intermediate playing operation, the controller 30 is in the position shown in Fig. 1 and so remains till the tone arm approaches the center of the record. In this position of the controller the arm 23 is in its clockwise pivoted position, the head 25 being so disposed that the projection 13 passes on the inner face of the head and the stop mechanism retains its inoperative position.

As the tone arm approaches the end of the playing groove, the arm 12 is moved therewith to be received between the fingers 33, thus moving the latch and releasing the engagement of the controller with the body 14. No movement of the controller, however, takes place until the final fast groove of the record gives the tone arm a final outward movement.

The final outward movement of the tone arm 10 moves the arm 12 which engages the outer finger 33 to move the controller 30 outwardly on the body 14 and to rotate the arm 23 whereby it will bring the head 25 in a position where the projection 13 will pass on the inner face of the head to further cam the arm 24, thus counter-clockwise pivoting the arm 23 whereby the projection 27 will strike the brake surface 39 and pivot the brake to its braking position, all as shown in Fig. 3.

In considering the structure and its operation it will be seen that the head 25 extends beyond the plane of the arm 24 whereby after actuation the projection 13 is released to rotate with the turntable. The device may thus be reset by the release of the brake and by the outward movement of the tone arm, which movement replaces the controller 30 by engagement of the arm 12 with the inner finger 33. It will further be seen that the elongation of the apertures 31 and 32 provides for a substantial flexibility of apertures as for instance the final groove may oscillate the tone arm without effecting the setting of the arm 23.

In considering the invention it will be understood that the invention is not confined to design of parts and structural details involved and that numerous changes and modifications and the full use of equivalents may be resorted to without departing from the spirit or scope of the present invention.

Having now described my invention, what I claim and desire to secure by Letters Patent, is:—

1. An automatic phonograph stop including a brake, a projection on the turntable, a

projection movable with the tone arm, an inter-engaging means actuated jointly by said projections to move said brake, said means including a controller engageable at 5 predetermined positions of the tone arm by the projection movable therewith, and means carried by said controller to prevent accidental movement thereof.

2. An automatic phonograph stop including a brake, a projection on the turntable, a projection movable with the tone arm, an inter-engaging means actuated jointly by said projections to move said brake, said means including a controller engageable at 15 predetermined positions of the tone arm by the projection movable therewith and a brake contacting arm associated with said controller, and means carried by said controller to prevent accidental movement 20 thereof.

3. An automatic phonograph stop including a brake, a projection on the turntable, a projection movable with the tone arm, an inter-engaging means actuated jointly by 25 said projections to move said brake, said means including a controller engageable at predetermined positions of the tone arm by the projection movable therewith and a brake contacting arm associated with said 30 controller and movable to apply the brake by the turntable projection, and means carried by said controller to prevent accidental movement thereof.

4. An automatic phonograph stop including a brake, a projection on the turntable, a projection movable with the tone arm, an inter-engaging means actuated jointly by 35 said projections to move said brake, said means including a controller engageable at predetermined positions of the tone arm by the projection movable therewith and a brake contacting arm associated with said controller and movable to apply the brake by the turntable projection, said controller 40 having lost motion connections to permit limited movement thereof without affecting said brake, and means carried by said controller to prevent accidental movement thereof.

5. A device of the character described including a body, a braking element carried thereby, an actuator mounted to actuate said braking element and a controller for setting said actuator, said controller being arranged 55 for movement by the tone arm and including means for locking the same against movement other than by said tone arm.

6. A device of the character described including a body, a braking element carried 60 thereby, an actuator mounted to actuate said braking element and a controller for setting said actuator, said actuator being positionable for movement by the turntable, said controller being arranged for movement by 65 the tone arm and including means for lock-

ing the same against movement other than by said tone arm.

7. A device of the character described including a body, a braking element carried thereby, an actuator mounted to actuate said braking element and a controller for setting said actuator, said actuator being positionable for movement by the turntable, said controller being arranged for movement by the tone arm, said actuator and controller 70 having a connection whereby said controller sets the position of said actuator, said controller including means for locking the same against movement other than by said tone arm.

8. A device of the character described including a body, a braking element carried thereby, an actuator mounted to actuate said braking element and a controller for setting said actuator, said actuator being 75 positionable for movement by the turntable, said controller being arranged for movement by the tone arm, said actuator and controller having a connection whereby said controller sets the position of said actuator, said connection having lost motion, said controller 80 including means for locking the same against movement other than by said tone arm.

9. A device of the character described, including a body, a brake element carried by 95 said body, detents on said body for limiting the movement of said brake element, a brake actuator mounted on said body, a detent on said body to limit the movement of said actuator, a controller slidably mounted on said body in operative relation with said actuator, said actuator and controller being 100 jointly operative by a turntable and tone arm respectively, and means carried by said controller to prevent movement thereof except by a tone arm.

This specification signed this 5th day of June, 1929.
